UNITED STATES PATENT OFFICE.

ANDREW J. COGLEY AND JOHN S. KENDIG, OF LANCASTER, PENNSYLVANIA.

SIGNAL-LANTERN.

SPECIFICATION forming part of Letters Patent No. 393,460, dated November 27, 1888.

Application filed September 10, 1887. Serial No. 249,288. (No model.)

To all whom it may concern:

Be it known that we, ANDREW J. COGLEY and JOHN S. KENDIG, of Lancaster, in the county of Lancaster and State of Pennsylvania, have invented certain new and useful Improvements in Signal-Lanterns; and we do hereby declare the following to be a full, clear, and exact description of the invention, such as will enable others skilled in the art to 10 which it appertains to make and use the same.

The object of our invention is to enable a signal-lantern burning coal-oil to be used in blasts of wind without affecting the light. To attain this end, we have devised the construction and 15 combination of parts hereinafter set forth and claimed.

In the accompanying drawings, Figure 1 represents a vertical section of the lantern cut through the cap and support. Fig. 2 represents a similar view taken at right angles to Fig. 1 through the center of the glass disk. Fig. 3 represents a horizontal section of the same, taken above the lamp. Fig. 4 represents a plan view of the lantern with the cover thrown back. Fig. 5 represents, on a smaller scale, an elevation of the lantern, taken from one of the sides having the glass disk.

A designates the rectangular casing of the lantern, having a bottom, A', in which are 20 holes a near two of its sides. On two opposite sides the lantern is provided with glass windows B, preferably circular, which are set into metallic annular sockets C, formed with casing A. These sockets are provided with 25 flanges c at their inner edges for preventing the glass from entering the lantern. To secure the glass externally, a ring, D, is inserted within said socket, bearing against the outer face of the peripheral part of the glass. The outer 30 edge of each ring D is bent over the projecting outer edge of said socket, rendering these parts of the lantern air-tight. One of the other sides of the casing A is provided with a socket, E, for receiving the upper end of a pole or 35 similar support. The fourth side of said casing A is provided with a hand-hole for inserting, withdrawing, and extinguishing the lamp. This is surrounded by an outwardly-extending collar, F, formed with said casing. A cap, 40 G, fits within said collar, its inner edge coming against a small internal annular flange, f, at the base of said collar, while the cap itself

is provided at its outer corner with a similar external flange, g, which fits against the outer edge of the collar, these flanges making the 55 joints air-tight. The cap G is provided with a handle, G'.

The perforations a in the bottom A', already referred to, are along the two sides of the lantern. They admit air into horizontal air-ducts H, which connect with vertical flues I, each consisting of several overlapping funnel-shaped tubes, i, extending upward along the inner face of the casing A on opposite sides thereof. The uppermost tube i on each side 60 is inclined toward the other flue I in a position more nearly horizontal than vertical. Where the upper tubes, i, of each side approach each other, a shield, J, is placed below and in front of their ends. 7C

The middle of the top of casing A is provided with an upwardly-extending truncated cone, K, open at the top. The upper edge of this truncated cone is provided with an annular flange, k, extending outward and downward as a wind-guard. Standards S, rising from the upper edge of said truncated cone, support a horizontal heat-guard, L, above the opening in the top thereof. A cover, M, having the shape of a cylindrical box open at the 80 bottom only, is hinged at m to the top of casing A, and secured thereto at an opposite point by a spring-catch, N, which allows said cover to be turned back at will. This cover has perforations m' in it near its base, which supply 85 air below the wind-guard, before mentioned. When secured by the spring-catch N, it encloses and protects the aforesaid cone, wind-guard, and heat-guard. It is provided with a bail, O, whereby the lantern is carried. Putty 90 is used for more effectually sealing the glass windows. The lamp P rests on the bottom A' within a socket, p.

The air enters only through the perforations a in the bottom A', whence it passes along 95 through air-ducts H and upward through flues I over the top of the fender J to the space above the lamp P, then up through the truncated cone K, and finally out through perforations m'. The wind-guard k prevents a sudden 100 blast of air from rushing in through these last-named perforations and descending on the lamp. The heat-guard L prevents the heat of the lamp from injuring the cover M. The

flame is effectually protected, by the construction above described, against sudden blasts of air, but may easily be extinguished at will by withdrawing the cap G and allowing air to 5 rush in.

Having thus described our invention, what we claim as new, and desire to secure by Letters Patent, is—

1. In combination with a lantern casing having an upwardly-extending cone, K, open at the top, and a deflector, k, flaring outwardly and downwardly from the edge of this opening, a cover, M, attached to said casing and inclosing said cone and deflector, said cover being provided with holes m' in its side below the level of said deflector, and the latter being imperforate and connected at its base to the top of the lantern-casing, in order that there may be no communication between the interior of 15 said casing and the holes m' , except through the top of said cone and above said deflector, substantially as set forth.

2. In combination with a lantern - casing

having openings for air in its bottom, a series of flues arranged above said openings, and an outlet for the air passing up through said flues, each flue consisting of a succession of overlapping funnel-shaped tubes or sections. 25

3. In combination with a lantern-casing having openings in its bottom, a pair of flues, each 3c consisting of successive funnel-shaped sections, cross-tubes extending inward from the upper ends of said flues, and a shield, J, protecting the inner ends of said cross-tubes, substantially as set forth.

In testimony whereof we have hereunto subscribed our names in the presence of subscribing witnesses.

ANDREW J. COGLEY.
JOHN S. KENDIG.
